vertical rear edges inturned to provide flanges interposed as spacers between the rear wall and the heat insulating lining.

2. A heated display case comprising a receptacle having a hinged top and a transparent front wall, said receptacle having a heat insulating lining, a light bulb mounted in said receptacle, a screen guard surrounding said bulb and means for energizing said light bulb, the two side walls of the receptacle having their vertical front edges inturned to form flanges, vertically disposed channel members positioned inside said flanges and U-shaped vertical channel members clamp-

ing said first channel members to said flanges, said transparent panel being retained within and between said first channel members.
